DOUBLE-ACTION PUMP

Glenn Dean Gibson, Minneapolis, Minn.

Application May 13, 1948, Serial No. 26,779

5 Claims. (Cl. 103—183)

1

This invention relates to double action pumps and particularly, to a pump which is actuated by the reciprocation of a plunger or the like.

It is an object of my present invention to provide a simple, sturdy and highly efficient double action pump adapted to simultaneously lift by force and by suction through the pump cylinders and comprising a minimum number of working parts.

Another object is the provision of a double action pump wherein a pair of valve-equipped pistons are reciprocated in opposite directions through simple interconnection of rack and pinion parts and wherein all parts are very compactly and efficiently housed within a common housing readily insertable within a well casing.

Another object is to provide a pump of the class described wherein flow of water during operation is substantially continuous and uniform without splashing or surging and wherein the relationship of pistons and valves is such that a very high efficiency and capacity is obtained.

Still another object is the provision of a double action pump completely housed and embodied in a unitary, compact, box-like casing with intake and discharge passages provided, thereby adapting the device for use in many types of wells and for connection with the conventional operating mechanisms and well casings now in use.

These and other advantages of my invention will more fully appear from the following description made in connection with the accompanying drawings wherein like reference characters refer to similar parts throughout the several views and in which:

Fig. 1 is a vertical section through a well showing an embodiment of my invention in side elevation, operatively attached to the vertical pipe of the system;

Fig. 2 is a vertical section taken transversely of the axle of the spur gear or pinion of my structure; and

Fig. 3 is a cross section taken on the line 3—3 of Fig. 2.

The embodiment of my double action pump illustrated is connected to the lower end of a conventional vertical pump pipe P mounted in a well casing W and supported at its upper end by a threaded collar C which rests upon a platform X. The upper end of pipe P is connected with a tubular casing Y having a dome D in the top thereof and the laterally and downwardly extending pump discharge Z. All of this structure is conventional and includes a vertical reciprocating pump rod R connected to the working

2

end of a pump lever L which is intermediately fulcrumed on a bracket B affixed to the medial portion of casing Y and which has the conventional handle H for actuating the pump rod.

5 The working parts of my double acting pump structure are encased in a very compact, unitary housing 5 of narrow box-like shape, having longitudinally drilled or otherwise formed in the upper end thereof, an upper cylinder 5a and having 10 formed therein, a lower cylinder 5b in the lower end. It will be noted that the cylinders 5a and 5b are disaligned but that their cross sectional areas materially overlap when viewed vertically downwardly. This construction and arrangement is responsible for extreme compactness in my structure and offers a factor of efficiency since driving connections between the two pistons of my pump is transmitted effectively thereby.

A longitudinal passage 5c is formed in the upper portion of casing 5 disposed in side by side relation with the upper end of the lower cylinder 5b. A similar passage 5d is formed in the lower portion of casing 5 extending upwardly from the end thereof into communication eccentrically

25 with the lower end of cylinder 5a. A hollow piston 6 is mounted for reciprocation in the upper cylinder 5a having a medially and transversely disposed valve seat 6a formed therein and as shown, centrally apertured to seat a ball valve 7.

30 An abutment element 8 is fixed to the inner periphery of piston 6 terminating in a position to restrict the upward movement of ball 7 relative to its seat to prevent displacement of the ball. A depending rack bar 9 is connected substantially axially with the lower end of piston 6 and as shown, is pivotally connected at its upper end by a wrist pin 9a, said bar carrying the rack at its inner side.

A lower hollow piston 10 is mounted for reciprocation in the lower cylinder 5b and as shown, has an annular valve seat 10a at its lower end which is adapted to receive a ball valve 11 disposed above said seat. An upstanding rack bar 12 is axially connected with the upper end of piston 10, as shown, by a pivot pin or wrist pin 12a. The rack bar 12 has teeth on the inner face thereof. The upper end of rack bar 12 as shown, is connected by a ball and socket joint with the lower end of the pump rod 13 which in 45 conventional manner, is accommodated within the vertical pipe P substantially axially thereof.

The housing 5 at its lower end, is closed as shown, by a valve-equipped liquid-intake block 14 which has a pair of spaced vertical liquid passages 14a and 14b in the upper portion thereof,

communicating respectively with the lower end of the passage 5d and the lower end of the lower cylinder 5b. Passages 14a and 14b are provided adjacent their lower ends with annular valve seats 14c and 14d respectively, which are cooperatively associated with ball valves 15 and 16 disposed thereabove. A small chamber 14e is formed in block 14 below passages 14a and 14b which is closed at its lower end save for communication through a nipple 14f with the liquid supply therebelow.

Casing 5 is closed at its upper end by a combined closure and discharge member indicated as an entirety by the numeral 17, comprising a horizontal plate 17a having integrally cast or otherwise affixed thereto, a branch discharge fitting 17b having a branch connected with the upper end of cylinder 5a and another branch extending axially of and connected with the upper end of the upper passage 5c.

The rack bars 9 and 12 are interconnected for joint operation in opposite directions by a pinion or spur gear 18 which is revolvably journaled on a pivot shaft 19 which extends through a closure plug 20 at one side of the casing and through an aperture formed in the opposite side of the casing. Plug 20 is of a diameter slightly greater than the pinion 18 to facilitate assembly of the working parts within the casing and as shown, has an annular sealing flange 20a adjacent the outer end thereof, which is set in a complementary shoulder afforded by the apertured portion of casing 5. The pivot shaft 19 as shown, is in the form of a headed bolt having the threaded end which is engaged by a nut 21 and the bolt and plug 20 securely clamped to the casing with sealing washers 22 interposed between the headed and nutted ends of the bolt and the adjacent sides of the casing.

Operation

In use, when the pump rod 13 is reciprocated, pistons 6 and 10 are moved in opposite directions within their respective cylinders 5a and 5b. Reciprocating power is directly applied to piston 10 through the rack bar 12 and is transmitted oppositely to piston 6 through the pinion 18 and rack bar 9. The rack bars 9 and 12 are precisely guided for longitudinal reciprocating movement by means of vertical channel guides 24 and 25 respectively, cast or otherwise formed on the medial portions of the side walls of housing 5. As shown, these channels are formed in inwardly extending lugs which preferably are apertured to permit free passage of liquid through the bodies thereof.

In the upward movement of each of the pistons 6 and 10, the ball valves 7 and 11 are closed and sealed against their respective seats and the action of the piston lifts the water above it, upwardly, while at the same time by suction, drawing water through the intake passages 14a and 14b as the case may be. In the downward strokes of pistons 6 and 10, the ball valves 7 and 11 are dislodged upwardly from their seats and check valves 15 and 16 in the intake of the housing, are closed.

It will be apparent that as piston 6 is moving upwardly in its cylinder 5a in the pumping stroke, the piston 10 is moving downwardly through the liquid contained in cylinder 5b. The result is that an almost continuous uniform discharge of liquid through pipe P is effected even when the pump rod 13 is reciprocated through a very short stroke.

The overlapping relationship of the paths of the two pistons 6 and 10 and their associated cylinders brings about an application of power through reciprocation of rod 13 axially of piston 10 and offset only a short distance from the longitudinal axis of piston 6. Furthermore, such arrangement enables my structure and the working parts thereof to be very closely compacted into a small unitary structure.

10 The entire mechanism may be very quickly assembled in a unitary housing; comprises a minimum number of working parts and is adapted to withstand long continued use. The co-operation of reciprocating piston parts, rack bars and efficient ball valves provides a high capacity, double acting pump wherein the valves are nicely sealed in their cycles of operation.

It will of course, be understood that various changes may be made in the form, details, arrangement and proportions of the parts without departing from the scope of my invention.

What I claim is:

1. A double acting pump comprising a unitary housing having a pair of cylinders formed therein, disposed with their axes in parallel relation, one of said cylinders being located adjacent one end of said housing and the other of said cylinders being located adjacent the opposite end of said housing, said casing having a discharge passage communicating with the delivery ends of said cylinders and having an intake passage communicating through branches with the intake ends of said cylinders, check valves disposed in the branches of said intake passage, pistons mounted for reciprocation in said cylinders and each having a liquid passage therethrough and a valve adapted to close said passage when the piston is moved towards the discharge end of its stroke, means extending beyond said housing for reciprocating one of said pistons and means mounted in said housing for interconnecting said pistons to drive said pistons in opposite directions, the inner ends of said cylinders being spaced apart in a direction longitudinally of said housing and said last mentioned means comprising a pinion interposed in said housing between the inner ends of said cylinders and longitudinal rack bars connected with each of said pistons and intermeshed with said pinion.

2. A double acting pump comprising a unitary housing having a pair of cylinders longitudinally formed therein and disposed with their axes in parallel relation but with their circumferences in overlapping relation, one of said cylinders being located adjacent one end of said housing and the other of said cylinders being located adjacent the opposite end of said housing the inner ends of said cylinders being spaced a short distance apart in a direction longitudinally of said housing, said casing having a discharge passage communicating with the delivery ends of said cylinders and having an intake passage communicating through branches with the intake ends of said cylinders, check valves disposed in the branches of said intake passage, pistons mounted for reciprocation in said cylinders and each having a liquid passage therethrough and a valve adapted to close said passage when the piston is moved towards the discharge end of its stroke, each of said pistons having a rack bar connected therewith, said rack bars being disposed in parallel relation with racks opposed and a pinion mounted within said housing and interposed between the inner ends of said cylinders

for interconnecting said rack bars to drive said pistons in opposite directions.

3. The structure set forth in claim 2 and means connected with one of said pistons for connection with a reciprocating rod extending beyond said housing to actuate said pistons.

4. A double acting pump comprising a casing having a pair of cylinders formed therein, with their axes in parallel relation but with their circumferences in overlapping relation, said casing having a discharge passage communicating with the delivery ends of said cylinders and having an intake passage communicating with the intake ends of said cylinders, pistons mounted for reciprocation in said cylinders and each having a liquid passage therethrough and a valve adapted to close said passage when the piston is moved towards the discharge end of its stroke, a pinion mounted medially of said casing within the same, with portions of its periphery exposed in said respective cylinders, a rack bar connected with one of said pistons and extending generally axially thereof and in mesh with one side of said pinion, an oppositely extending rack bar connected with the other of said pistons and extending generally axially thereof and being in mesh with the opposite portion of the periphery of said pinion, a reciprocable actuating rod connected with one of said rack bars, and check valves in the intake passages of said cylinder.

5. A double acting pump comprising a housing

having a pair of cylinders therein disposed with their axes in parallel relation but with their circumferences in overlapping relation, one of cylinders being disposed adjacent one end of said housing and the other of said cylinders being disposed adjacent the opposite end of said housing, said casing having a discharge passage communicating with the delivery end of said cylinders and having an intake passage communicating with the intake ends of said cylinders, pistons mounted for reciprocation in said cylinders and each having a liquid passage therethrough and a valve adapted to close said passage when the piston is moved towards the discharge end of its stroke, each of said pistons having a rack bar connected therewith, said rack bars being disposed in parallel relation with racks opposed and a pinion journaled intermediately of the ends of said rack bars and intermeshed with the racks thereof for interconnecting said rack bars to drive said pistons in opposite directions.
